UNITED STATES PATENT OFFICE.

ORVILLE COOLEY AND EDWARD PRIDMORE, OF BATAVIA, NEW YORK, AS
SIGNORS TO THE JOHNSTON HARVESTER COMPANY, OF SAME PLACE.

GRAIN-BINDING HARVESTER.

SPECIFICATION forming part of Letters Patent No. 408,163, dated July 30, 1889.

Application filed January 5, 1888. Serial No. 259,918. (No model.)

To all whom it may concern:

Be it known that we, ORVILLE COOLEY and EDWARD PRIDMORE, citizens of the United States, residing at Batavia, in the county of Genesee and State of New York, have invented a new and useful Improvement in 5 Grain-Binding Harvesters, of which the following is a specification.

Our invention relates to certain improvements in grain-binding harvesters of the Appleby type; but is more especially applicable to the machines manufactured by the Johnston Harvester Company, and known as "channel-steel grain-binders;" and the objects 10 of the improvements are, first, to provide means for securely fastening the finger-bar to the platform of the harvester-frame and still permit the edge of the canvas-rake to be brought in close proximity with the cutting-blades; second, to afford facilities for increasing or lessening the space between the 15 upper end of the binder platform or deck and corresponding end of the elevating-apron that brings the inflowing grain in proper position for binding, thereby adapting the machine for operating in different grades and kinds of grain without choking by the lodgment of matter within the open space found between the said deck and elevating-apron. 20 We attain these objects by the mechanism 25 illustrated in the accompanying drawings, in which—

Figure 1 is a sectional perspective view of a portion of a self-binding harvester, showing 30 our improved parts in position. Fig. 2 is a bottom view of a portion of the cutting apparatus, as well as a part of the harvester-platform, and showing the manner of attaching the supplementary finger-bars thereto. Fig. 35 3 is a detached view of a portion of the adjustable cleat or throat-bar that secures the binder-deck to the frame-work of the harvester. Fig. 4 is a cross-sectional view taken 40 through the finger-bar and supplemental finger-bar, as well as through the platform, and therewith showing a part of one of the canvas-rollers in position. Fig. 5 is a cross-sectional view taken through the binder-deck and contiguous parts.

Similar letters refer to similar parts throughout the several views.

In the drawings, A represents the finger-bar; A', the supplemental finger-bar, preferably made of a single piece of thin steel, which is firmly bolted or otherwise secured to the 55 rear face of the usual angle-iron finger-bar, and extends downward therefrom to give sufficient space between the canvas-propelling roller B and the upper face of the platform C for the revolving of the said endless canvas, 60 which is of the well-known Appleby type.

For the purpose of forming a support for the forward side of the platform C, a rearward bend is given this supplementary bar upon an angle corresponding with the beveled edge of the platform, as shown in Fig. 4. The platform and supplemental bar are fastened together by the use of rivets c, whereby the said platform and finger-bar are securely united without the intervention of the usual 70 wooden bar, which is bolted to the rear face of the angle-iron finger-bar and having the platform nailed at its front edge to the said wooden bar and upon the under side thereof. By the removal of this commonly-used wooden 75 bar the front edge of the revolving platform-canvas is brought about one and one-half inch nearer the finger-bar and the cutting-knives than would be done were the said wooden bar used. This wooden bar is objectionable on account of its coming in contact with the butts of the moving grain, extending the same and causing the head ends of the stalks of grain to advance to such a degree 80 that it is difficult to properly bind the bundle 85 without waste of grain.

By having the guard-fingers secured upon the under side of the horizontal flange at the bottom of the vertical flange the cutting apparatus is brought considerably nearer the 90 ground than would be the case were the fingers secured to a flange placed upon the upper side of the vertical one. This feature is important where short grain is to be cut and bound.

By having the supplementary bar secured to the vertical flange upon the rear side the platform and other accessories can be per-

manently attached to the supplementary bar, after which the finger-bar, with its attached fingers, may be bolted to the supplementary bar, (now forming a part of the complete machine,) or can be removed therefrom without any disarrangement of the parts, as in practice the nuts of the finger-bar-securing bolts are upon the face of the vertical flange and easy of access, which is an important feature, as the finger-bar has to be frequently removed for repairs by reason of its exposed position.

D is an adjustable cleat or thin bar, preferably made of metal, under which the upper end of the binder deck or platform lies, by which it is held down flush with the angle-bar d on the elevator-frame. Said cleat is provided with securing-bolts, which pass through the elongated holes d' in the cleat and through bolt-holes made in the angle-bar. This adjustable cleat, which forms the basis for the second part of our invention, rests solely upon the angle-bar d, and is adjustably secured thereto in such manner that the deck-platform may, if desired, have the usual fore-and-aft adjustment underneath the cleat and is for the purpose of covering the open space between the upper edge of the deck-boards and the cleat angle-bar, the cleat being provided with the elongated slots, so that when foul matter—such as weeds, grass, &c.—is found in the grain the cleat-bar may be moved downward, (by loosening the nuts upon the securing-bolts,) thereby enlarging the throatway, so as to allow the said foul matter to drop through and upon the ground; otherwise it is liable to accumulate and wedge in the space and stop the revolving elevating-canvas.

When the grain is in good condition, the cleat-bar is placed nearer the elevating-can-

vas roller than when operating in weedy material, thereby narrowing the throatway, so that all material raised by the elevating-canvas is deposited upon the deck-boards preparatory to binding, without waste, of which there would be danger were the throatway to be at all times enlarged for dropping the foul matter hereinbefore referred to.

Having now described our invention, what we claim as new, and desire to secure by Letters Patent, is—

1. The combination, with the single right-angled finger-bar having the guard-fingers bolted to the under side of the horizontal flange at the bottom of the vertical flange of the bar, of the metallic supplementary angle-bar made from a single piece of metal, the front vertical face of which is secured to the rear face of the vertical flange of the finger-bar, and therefrom extending downward sufficiently far to permit the attachment of the front side of the platform, which rests upon and is secured to the rearwardly-extending bend, forming a part of the said supplementary bar, in the manner substantially as described, and for the purpose hereinbefore set forth.

2. The combination, with the elevating-apron roller and binder-deck, of the slotted adjustable cleat-bar for regulating the opening between the elevating-apron roller and the upper edge of the binding-deck, for the purpose described, and substantially as hereinbefore set forth.

ORVILLE COOLEY.
EDWARD PRIDMORE.
